UNITED STATES PATENT OFFICE.

EBEN M. SCOTT, OF BRIDGEPORT, CONNECTICUT, ASSIGNOR TO THE
WARNER BROTHERS COMPANY, OF SAME PLACE.

PAPER BOX.

SPECIFICATION forming part of Letters Patent No. 670,690, dated March 26, 1901.

Application filed March 21, 1900. Serial No. 9,541. (No model.)

To all whom it may concern:

Be it known that I, EBEN M. SCOTT, a citizen of the United States, residing at Bridgeport, in the county of Fairfield and State of Connecticut, have invented a new and useful Improvement in Paper Boxes, of which the following is a full, clear, and exact specification.

My invention relates to that class of paper boxes in which the box slips within a tubular cover and is designed to provide a box which will be strong and light, easily opened, yet practically impossible of opening accidentally. Such a box has long been desired for many purposes, and especially for sending articles through the mail, where it is desirable that the contents of the box be easily inspected yet safe from accidentally falling out. I accomplish these objects by my invention, which is fully illustrated in the drawings and which I shall hereinafter describe.

Figure 1 is a perspective of the box, showing the arrangement of lids. Fig. 2 is a plan view of one side of the tubular cover, showing the locking-tongue. Fig. 3 is a sectional view of a box and cover along the lines 3 3 of Fig. 2.

Similar letters indicate similar parts throughout the several views.

The body of the box illustrated in Fig. 1 has sides *a a*, which may be secured together in any desirable manner. Preferably the sides and lids hereinafter referred to are in one piece, properly scored and cut. Each side has an extension or extensions forming a lid or lids *b* and adapted in size to nearly cover the top or bottom of the box when folded down thereon. These lids are folded down one upon the other, forming a four-fold thickness for the top or bottom of the box and making it impossible for the contents of the box to escape when the lids are firmly fastened. The lid forming the extreme top or bottom has in it a slit or opening *c*, the purpose of which will be hereinafter set forth. The tubular cover illustrated in plan in Fig. 2 is adapted in size to fit the box and is made in any desired manner, the blank being preferably oblong in shape, properly scored and creased, and fastened to keep its tubular shape.

On the upper or lower side of the tubular

cover, or both, are tongues *d d*, adapted to engage the slit or opening *c* of the lid *b* of the box when the latter is slipped within the tubular cover. These tongues are easily disengaged from the slit or opening, the box readily removed, and the contents inspected. It is obvious, however, that when the tongues are in engagement with the slits the box cannot be removed by any ordinary force.

The box may have the plurality of lids at either or both ends or may have only one lid at each end or may have one end uncovered or either end may be permanently closed in any desirable manner without departing from the spirit of my invention, the essential feature being a part having a slit or opening to engage the tongue of the tubular cover. It is also obvious that there may be one or more tongues on the tubular cover, the preferable form having two tongues, one on each side and at opposite ends of the cover, as illustrated in Fig. 2, one tongue being shown in dotted lines therein.

Having described my invention, what I claim, and desire to secure by Letters Patent of the United States, is—

1. The combination of a box with a tubular cover therefor, said box having a plurality of lids one of said lids being provided with means for detachably engaging the same with the tubular cover, substantially as described.

2. The combination of a box with a tubular cover therefor, said box having a plurality of lids more than one of which is provided with means for detachably engaging the same with the tubular cover, substantially as described.

3. The combination of a box with a tubular cover, said cover being provided with tongues one on each side and at opposite ends, said tongues being adapted to detachably engage with corresponding parts in the lids of the box, substantially as described.

4. The combination of a box with a tubular cover therefor, said box having a plurality of lids more than one of which is provided with means for engaging corresponding tongues on the tubular cover to detachably lock the same together, substantially as described.

5. The combination of a box with a tubu-

lar cover therefor, said cover being provided with a plurality of tongues one at each end and on opposite sides thereof adapted to engage the box at different points, substantially as described.

6. The combination of a box with a tubular cover therefor, said cover being provided with a plurality of tongues arranged on different sides thereof and at opposite ends and

adapted to engage corresponding parts of the box, substantially as described.

In witness whereof I have hereunto signed my name in the presence of two witnesses.

EBEN M. SCOTT.
